Primary Examiner — Bao-Yen T Nguyen*Assistant Examiner* — Amanda J Berlinski(74) *Attorney, Agent, or Firm* — WELSH FLAXMAN & GITLER LLC(57) **CLAIM**

The ornamental design for an ear pick, as shown and described.

DESCRIPTION

FIG. 1 is a side view of an ear pick wherein the opposite side view is an identical mirror image thereof;

FIG. 2 is a rear view of the ear pick;

FIG. 3 is a front view of the ear pick;

FIG. 4 is a top view of the ear pick;

FIG. 5 is a bottom view of the ear pick;

FIG. 6 is an enlarged partial view of the head section of the ear pick taken from FIG. 1;

FIG. 7 is a cross sectional view of the ear pick taken across the line 7-7 in FIG. 4;

FIG. 8 is an enlarged front view of the partial view of the head section of the ear pick as seen in FIG. 6;

FIG. 9 is cross-sectional view of the ear pick taken across the line 9-9 in FIG. 10; and,

FIG. 10 is a perspective view of the cross-sectional view of the ear pick in FIG. 7.

The broken lines shown in the figures are included to identify areas of enlargement and form no part of the claimed design.
